SAFETY RAZOR

John H. Woods, Lynbrook, N. Y., assignor to Ray
D. Lillibrige, Greenwich, Conn.

Application April 15, 1933, Serial No. 666,361

4 Claims. (Cl. 30—12)

This invention relates to safety razors and more particularly to safety razors of the type having a foldable or collapsible handle which serves also as a container or casing of a shape 5 suitable to display advertising matter, and which may be manufactured cheaply enough to be sold at a nominal price or given away as an advertisement and it is an object of this invention to provide an improved razor of the type 10 described in which the flexible material forming the casing or handle is creased or scored so as to fold in a manner forming a substantially rigid handle when in use without materially lessening the facility with which it folds in order to form 15 the container or casing when not in use. It is also an object of this invention to provide an improved blade holder which secures the blade in proper position for use.

In the drawings—

Fig. 1 is a view in front elevation of a safety razor constructed in accordance with this invention, shown as held for use;

Fig. 2 is a view in side elevation of the safety razor shown in Fig. 1;

Fig. 3 is a perspective view with the handle folded or collapsed as a casing when not in use;

Figs. 4 and 5 are vertical sections taken on the lines 4—4 and 5—5, respectively, of Figure 1;

Fig. 6 is a plan view of a blade holder with 30 a blade thereon, the blade being partly broken away to show parts of the holder;

Figs. 7, 8 and 9 are plan views of the blanks or sheets from which the handles or casings are formed and showing the scorings and slots used 35 in forming different modifications of this invention;

Fig. 10 is a view in elevation showing the blank of Fig. 7 as folded when in use;

Figs. 11, 12 and 13 are sections taken on lines 40 11—11, 12—12 and 13—13, respectively, of Fig. 10;

Fig. 14 is a view, similar to Fig. 10, of the modification shown in Fig. 8;

Figs. 15, 16 and 17 are sections taken on lines 45 15—15, 16—16 and 17—17, respectively, of Fig. 14;

Fig. 18 is a view, similar to Fig. 10, of the modification shown in Fig. 9; and

Figs. 19 and 20 are sections taken on lines 50 19—19 and 20—20 respectively, of Fig. 18.

As shown in the drawings a safety razor constructed in accordance with this invention comprises a single-edged blade 1 which may be of a usual type of thin flexible or stiff blade, a 55 blade holder 2 which secures the blade 1 in po-

sition and a sheet 3 of flexible material, such as cardboard or fiber-board, which is somewhat more flexible than the cardboards commonly used in paper boxes and which is suitably treated, as with paraffin, in order to render the cardboard more resistant to moisture, if desired. The blade holder 2 may be formed from sheet metal and has the usual guard portion 4, clips 6 which are stamped out of the body 5 of the blade holder and aid in positioning the blade, 10 a depression or boss 7 positioned between the clips 6 and having a tongue 8 struck out from the bottom portion thereof and a rounded edge 10 which has the tongues 12 struck out therefrom. The tongues 8 and 12 engage with an end 15 of the sheet 3 to secure the sheet to the blade holder. The blade holder is also provided with a lug or boss 14 which projects upwardly from the blade holder 2 to engage in an opening in the blade 1 and prevent removal of the blade from 20 the holder.

As shown in Figs. 7, 8 and 9 the sheet 3 is provided with perforations 16 to receive the tongues 8 and 12 and is scored or creased so as to cause the sheet to fold in a predetermined way 25 when used as a handle. As shown in Fig. 7, the scorings 18 may be parallel, extending longitudinally of the sheet adjacent the center thereof and ending at parallel slots 20 and 21 which extend transversely of the sheet. From the ends 30 of the slot 20 extend the scores or creases 22 which diverge to the side edges of the sheet 3 in the region of the blade holder, while from the ends of the slot 21 diverging scores or creases 23 extend to the end of the sheet. In the modification shown in Figure 8, the longitudinally extending scores or creases 18' diverge from the slot 20 to the slot 21', the slot 21' in this case being of greater length than the slot 21. Scores or creases 22 diverge from the ends of the slot 40 20 to the side edges of the sheet while the creases 23 diverge from the ends of slot 21' to the end of the sheet. In the modification shown in Figure 9 there is provided a central longitudinally extending score or crease 18a and diverging side creases 18b, all of the scores or creases extending from slot 20 to the far end of the sheet 3. Diverging scores or creases 22 extend from the ends of the slot 20 to the side edges of the sheet 3.

When assembled, the blade holder 2 is secured to the sheet 3 by means of the tongues 8 and 12, tongue 8 passing through the opening adjacent the slot 20, while the tongues 12 extend through the openings 16, the ends of the tongues being 55

bent down as shown in Figs. 2 and 5. The tongues hold the end of the sheet 3 bent about the curved portion 10 of the blade holder with an edge portion of the sheet 3 projecting partly over the blade 1 and forming a flap with which the opposite edge of the sheet may be engaged. When the razor is to be used sheet 3 is extended as shown in Figures 1 and 2 and the side portions of the sheet beyond the scores or creases 18 are engaged by the hand of the user, causing the sheet 3 to fold along the creases 22, 18 and 23. As shown in Figs. 10 to 13, the modification shown in Figure 7 will, under these conditions, provide a handle having a substantially flat longitudinally extending center portion 180 included between the slots 20 and 21 and the parallel longitudinally extending creases 18, while the side portions 19 of the sheet outside of the creases 18 form longitudinally extending flanges. The portion 180 of the sheet comprised between the creases 18 provides stiffness for the handle against lateral bending while the side portions 19 provide stiffness against bending in a plane perpendicular to the plane of the portion 180 so that the sheet, when folded, gives a rigid handle of substantially a hollow beam shape, with the portion 180 as the web.

Figures 14 to 17 show that the modification of Figure 8 assumes substantially the same shape as that of the modification of Figure 7 when folded as a handle except that the portion 180' comprised between the scores or creases 18' tapers towards the blade holder, but as in the previous modification, this portion provides stiffness against lateral bending and the side portions 19' provide stiffness in a direction perpendicular to the plane of the portion 180'.

In the modification shown in Figure 9 the portions 180_a of the sheet comprised between the side creases or scores 18_b and the center crease 18_a taper and are inclined to the central score or crease 18_a, but in this modification, as in the others, the position of the portions 180_a provides stiffness against lateral bending and the side portions 19_a provide stiffness in a direction substantially perpendicular to the plane of the portions 180_a.

In each of the modifications the slot 20 at the blade holder end of the sheet 3 and the slot 21 or 21' at the other end of the sheet in the modifications shown in Figures 7 and 8, frees the ends of the portions 180, 180' and 180_a of the sheet between the scores or creases 18, 18' or 18_b respectively and prevents the distortion of this portion by stresses which, if transmitted thereto, would tend to distort the shape of these portions and to lessen their resistance to lateral bending.

The scores or creases 22 extend the portions 19, 19' and 19_a beneath the portions secured to the blade holder 2 so as to support these portions when the razor is in use and the divergence of these scores gives a tapering of the side portions which causes the blade holder 2 to be inclined to the handle at the most effective angle for use of the razor.

No scoring or creasing of the sheet 3 is necessary in order that it may be folded into the position shown in Fig. 3 and the scores or creases described in no way affect this folding of the sheet 3 once the portion thereof which forms the handle is restored to a flat condition as shown in Figs. 7, 8 and 9.

What is claimed is—

1. A safety razor including a sheet of flexible material having a fold at one end forming a blade receiving pocket and the remainder of said sheet having spaced scores or creases extending longitudinally thereof to shape said sheet as a beam resisting lateral bending when folded along said scores or creases for use as a handle, said sheet having means extending between said creases and defining part of an end of the beam.

2. A safety razor including a sheet of flexible material having a fold at one end to form a pocket receiving a blade and the remainder of said sheet having spaced scores or creases extending longitudinally thereof to shape said sheet as a beam resisting lateral bending when folded along said creases for use as a handle and slots extending between said creases and separating parts of the ends of said beam from said sheet.

3. A safety razor including a sheet of flexible material having a fold at one end to form a pocket receiving a blade and the remainder of said sheet having spaced scores or creases extending longitudinally thereof to shape said sheet as a beam resisting lateral bending when folded along said creases for use as a handle, a slot extending between said creases and separating part of an end of said beam from the sheet and creases along which the sheet tends to fold when in use as a handle diverging from the ends of said slot.

4. A safety razor including a sheet of flexible material having a fold at one end to form a pocket receiving a blade and having the remainder of said sheet form a handle, said handle having a central longitudinally extending crease and side creases spaced from said central crease, said side creases diverging toward the free end of said handle and with said central crease shaping said sheet as a beam resisting lateral bending when said sheet is folded along said creases for use as a handle.

JOHN H. WOODS.
